UNITED STATES PATENT OFFICE

2,520,549

SPOUT, INCLUDING A SPLIT CIRCULAR CHANNEL-SHAPED ATTACHING BAND

Harold E. Jacobsen, Kingsley, Mich.

Application July 2, 1947, Serial No. 758,497

5 Claims. (Cl. 222—569)

1

This invention relates to new and useful improvements in spouts and more particularly to a detachable spout for containers.

The primary feature of the present invention is to provide a spout including a split circular channel-shaped attaching band which is so designed as to frictionally grip the edge of the opening in the container.

Another important feature of the present invention is to provide a device of the character referred to which replaces the usual cover of a paint can or the like and when properly tightened will provide a solid and practical pouring spout which will eliminate waste and drippings caused when heavy liquids are poured from a full can of the ordinary flat top variety.

A further feature of the present invention is to provide a spout that is quickly attached to a container or removed from the container, and said spout extending upwardly and outwardly at a slight angle with the container so that any liquid on the spout will conveniently drain back into the interior of the container when the container is placed with its bottom on a flat surface.

A still further feature of the present invention is to provide a spout that is simple and practical in construction, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the improved spout applied to a usual flat top container having its cover removed therefrom to accommodate the spout;

Figure 2 is a fragmentary side elevational view of Figure 1;

Figure 3 is a rear view of Figure 1;

Figure 4 is a longitudinal vertical sectional view taken substantially on the plane of section line 4—4 of Figure 1;

Figure 5 is a transverse vertical sectional view taken substantially on the plane of section line 5—5 of Figure 2;

Figure 6 is a fragmentary perspective view of the rear portion of the spout, and showing the manner in which the band is retained in position to the container;

Figure 7 is a fragmentary top plan view showing the band in a completely expanded position; and,

2

Figure 8 is a fragmentary top plan view showing the locking means for retaining the band in position to the container in slightly modified form.

Referring now to the drawings in detail, wherein for the purpose of illustration, there is disclosed a preferred embodiment of the present invention, the numeral 10 represents a circular band substantially channel-shaped in cross section and split at its rear portion to form adjacent edges 12 and 14.

Integrally formed with the band 10 is a substantially concavo-convex surface forming a spout 16, that extends slightly upwardly and forwardly at an inclined angle with the horizontal plane of the band and said spout is provided with a vent or arcuate cut-out portion 17 at its rear end. The forward end of the spout terminates in a nipple 19 that projects outwardly from the band, as best shown in Figures 1 and 2 of the drawings.

In order to use the spout attachment it is first necessary to remove the cover normally held at the upper end of a substantially flat top container 18, so that the band may snugly grip the inner edge 20 of the opening provided in the top of the container when the cover therefor is removed.

A sealing compound 22 of any suitable type is preferably placed on the inner side of the band to tightly adhere to the edge 20 for holding the band in position thereto and to prevent liquid in the container from passing outwardly through the band.

Reference is now directed to Figure 6, wherein there is disclosed the locking means for frictionally retaining the band in position to the container.

The numeral 24 represents a flat substantially rectangular arm having a centrally disposed outwardly projecting sleeve 26 at one terminal portion, that extends between a pair of spaced parallel sleeves 28 at the vertical edge 12 of the band. A pin 30 extends between sleeve 26 and 28 to hingedly connect arm 24 to the band.

Projecting outwardly from substantially the center of arm 24 is a pair of spaced parallel sleeves 32 between which extends the centrally disposed outwardly projecting sleeve 34 at one terminal end of a second arm 36. A pivot pin 38 hingedly connects the arm 36 to the arm 24.

A sleeve (not shown) projects outwardly from the opposite end of arm 36 and is pivotally mounted by a pin 40 between the spaced parallel sleeves 42 projecting outwardly from the vertical edge 14 of the band.

A finger gripping knob 44 is carried by the

free end of arm 24 for actuation of the arms to spread or contract the band.

By pushing outwardly with knob 44 one face of arm 24 will bear against one face of arm 36 whereby the band will be spread to frictionally engage the edge 20 of the container.

To release the band from the container, it is merely necessary to pull the knob 44 inwardly whereby the band will be contracted to disengage edge 20 of the container.

Reference is now directed to Figure 8, wherein there is disclosed a modified means for locking the band 10 to the container top. In this form, a pair of spring arms 46 and 48 are suitably secured to the adjacent edges 12 and 14 of the band and the free ends of these arms project into the opening of the top of the container when the band is applied to the edge 20 of the container. Finger gripping knobs 50 are provided at the free ends of these arms to facilitate contracting the band for engagement with or removal from the edge 20 of the container. The band being of such resiliency to normally frictionally engage the edge of the container.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A device of the class described comprising a split band of resilient material adapted to grip the inner edge of the opening in a container, an upwardly and outwardly inclined pouring nipple integrally formed with the band for pouring liquid held in the container, a cover integrally formed with said band and said nipple and forming a baffle for directing liquid to said nipple during the pouring of liquid from the container, and fastening means holding the ends of the band together, said cover having an opening surrounding the fastening means and permitting access to the fastening means.

2. A device of the class described comprising a channel-shaped band in cross section adapted to grip the inner edge of the opening in a container, an upwardly and outwardly inclined spout integrally formed with the band for pouring liquid from the container, and a cover integrally formed with said band and forming a baffle for directing liquid to said spout during the pouring of a liquid from the container.

3. A device of the class described comprising a channel-shaped band in cross section adapted to engage the inner edge of the opening in a container, said band being arcuate and having spaced end portions an upwardly and outwardly inclined spout integrally formed with the band for pouring liquid out of the container, said spout having a concavo-convex rear portion, and a vent provided at the rear portion of said spout to facilitate easy pouring of the liquid in the container and for visibility into the container.

4. A device of the class described comprising a circular band channel-shaped in cross section adapted to engage the inner edge of the opening in a container, said rear portion of the band being split to provide adjacent edges, an arm pivoted at one end to one of said edges, a second arm pivoted to said opposite edge, the free end of said second arm being pivoted to said first arm, finger gripping means carried by the free end of said first arm for actuation of said arms, and an upwardly and forwardly inclined spout integrally formed with the band for pouring liquid from the container, said spout including a rear portion overlying the band, said rear portion having a vent disposed diametrically opposite from the spout to facilitate easy pouring of the liquid from the container and for visibility into the container.

5. A device of the class described comprising a circular band channel-shaped in cross section adapted to engage the inner edge of the opening in a container, said rear portion of the band being split to provide adjacent edges, means for spreading and contracting said band, and an upwardly and forwardly inclined substantially concavo-convex spout integrally formed with the band for pouring liquid from the container, said band provided with a sealing compound for adhering the band to the inner edge of the opening in the container.

HAROLD E. JACOBSEN.
